UNITED STATES PATENT OFFICE

2,101,334

STRIP FEEDING MECHANISM FOR WRITING MACHINES

Walter Elmer Gechnauer, Dover, N. H., assignor to American Sales Book Company, Inc., Niagara Falls, N. Y., a corporation of Delaware

Application August 1, 1935, Serial No. 34,242

13 Claims. (Cl. 271—2.4)

This invention relates to improvements in writing machines, such as autographic registers and the like, and more particularly to an improved assembly and arrangement of the feed mechanism for feeding into position the record strips which are used in the manifolding operations.

It is a general object of the invention to provide an improved arrangement and assembly of the elements of the strip feeding mechanism whereby such elements not only are maintained in their correct operative position, but also they may be assembled or disassembled or adjusted in an improved manner and with a saving of time and energy over prior existing devices of this character.

Another object of the invention is to provide improved means whereby the operative elements of the feed mechanism, as the feed disks, may be readily mounted upon the feed shaft or adjusted thereon and locked in their operative adjusted position.

According to another feature of improvement, a polygonal or other non-circular feed operating shaft is mounted in the supporting frame by an improved arrangement of bearings and the feed controlling elements are adjustably mounted upon said shaft by means of an improved supporting arrangement.

Another object is to provide an improved adjusting arrangement for the strip feed disks whereby said disks may be quickly and easily adjusted upon the feed shaft for the accommodation of record strips of different widths.

Other objects of the invention will be in part pointed out in the following detailed description of certain illustrative but preferred embodiments of the invention, and will be in part obvious in connection therewith.

The invention accordingly comprises the features of construction, combination of elements and arrangement of parts which will be exemplified in the construction hereinafter set forth, and the scope of the application of which will be indicated in the claims.

For a more complete understanding of the nature and objects of the invention, reference is had to the following detailed description, and to the accompanying drawing, in which:

Fig. 1 is a transverse vertical section through a record machine of the autographic register type equipped with the invention, the section being taken approximately along the axis of the feed shaft, and parts being shown in elevation;

Fig. 2 is a fragmentary, transverse section of

the feed shaft showing in elevation the attachment of one of the feed disks; and

Fig. 3 is a fragmentary section similar to Fig. 1 but showing a modified embodiment of the invention.

Although the improved feeding mechanism may be used in connection with various machines, it is herein disclosed as installed in a record or writing machine of the autographic register type, of the general nature disclosed in Patent No. 10 1,827,745, L. F. Hagemann, dated October 20, 1931. As in the Hagemann patent, the feeding mechanism is operated by a handle of the reciprocating lever type, but it will be obvious that other types of operating means are applicable.

As shown in the drawing, there is a supporting frame 5 for the feed assembly mounted within a casing 6 which provides a housing for the operative elements. This frame may be mounted in the casing for installation or removal as a unit, 20 as by means of supporting blocks 7 attached to the bottom of the casing and to which the side frame members of the frame may be detachably connected in any convenient manner. A platen (not shown) may be provided as in the Hagemann 25 patent mentioned for supporting the record strips in position for the reception of inscriptions, and these strips are fed forwardly from a supply into writing position by means of the feeding mechanism. The frame 5 is provided with transversely 30 aligned bearings 8 rotatably supporting the feed shaft 9 which carries transversely spaced feed disks 10 cooperating with a feed roll 11 mounted in a feed roll carrier or housing 12 and yieldingly urged into gripping relation with the disks by 35 means of springs 13. By means of this arrangement, the work webs or record strips will be gripped between the feed disks and the feed roll and thus fed forwardly upon rotation of the feed shaft in a manner fully disclosed in the Hagemann 40 patent mentioned. Also, an additional disk 14 may be mounted upon the feed shaft 9 between and in spaced relation with the feed disks 10. This disk 14 may be equipped with strip folding mechanism, such, for example, as disclosed in Patent No. 1,658,127, C. L. Johnston, issued February 17, 1928. The strip feeding and folding disks are mounted for rotation with the feed shaft 9.

As shown in the drawing, the shaft 9 is polygonal in cross-section, preferably hexagonal, although it may be of some equivalent non-circular cross-section so that the disks and other elements having correspondingly shaped apertures when mounted upon the shaft are held against relative 55

rotation. In other words, the shaft is formed with one or more longitudinal ribs positioned parallel to the shaft axis and formed at the apices of the polygonal shaft in the embodiment shown. 5 This rib cooperates with the complementary openings of the disk apertures to provide for adjustment of the disks along the shaft into different operative positions, but said rib functions to restrain relative rotation between the 10 shaft and disks. The feed shaft is rotatably mounted in the bearings 8 by means of bearing elements 15 and 16 which are provided with hexagonal openings whereby they may be slid onto the opposite ends of the shaft and thus held against 15 relative rotation thereon. The bearing element 15 as shown is preferably formed as an integral extension of the driving member 17 which is operatively connected to the operating handle. In 20 a similar manner the bearing element 16 is constructed integrally with the cam element 18 which may be utilized in driving a part of the mechanism of the complete machine. This arrangement of the bearings 15 and 16 enables them to be assembled with the shaft or disassembled very 25 quickly and easily.

Also the construction and arrangement of the means for attaching the disks 10 and 14 on the main driving shaft 9 provides not only for ready 30 assembly or disassembly, but enables these disks to be adjusted longitudinally of the shaft 9 to accommodate different widths of record strips and to be firmly attached in adjusted position.

This attaching means is similar for each of the disks, and in the embodiment of Figs. 1 and 2 35 includes a mounting and supporting hub 19 having an inclined supporting surface, preferably a conical surface for supporting the disk. This hub is provided with an aperture of the same shape as the shaft 9 in cross-section, and this 40 aperture receives the shaft thus locking the hub against relative rotation while the hub is readily slideable along the shaft. Each hub is provided with a longitudinal slot 20 preferably axially disposed as shown, and extending throughout the diameter 45 of the hub but terminating a short distance from one end thereof so as to leave a small integral supporting section 21 adapted to hold the oppositely disposed parts of the hub together in a unit. The slot 20 divides the hub substantially into its opposing halves or sections attached by the supporting section 21. By means of this arrangement 50 the two opposite hub sections are inwardly yieldable, whereby the hub aperture may be contracted so as to grip the hub in adjusted position upon the shaft. Each of the disks 10 and 14 is provided 55 with a mounting hub 22 having a conical aperture complementary with the conical surface of the hub 19 and shaped and proportioned for the reception of the latter so as to support the disk 60 upon its supporting hub. At its small end, each conical hub 19 is threaded for the reception of a threaded nut 23 which is adapted to engage the adjacent end of the disk hub 22 so as to force the latter into assembled position upon the supporting hub 19. By means of the hub assembly 65 described, it will be noted that each of the disks 10 and 14 may be conveniently assembled with the driving shaft 9 and locked in assembled position thereon in any desired spaced relation. When a 70 disk has been adjusted along the shaft into its final desired position, the nut 23 will be tightened to force the conical surface of the disk hub 22 into cooperative contact with the conical surface of the supporting hub 19, thus causing contraction of the latter and firmly gripping and holding 75

the disk permanently in its operative position. By means of this arrangement, the assembly and adjustment of the parts are very easy of accomplishment. If it is desired to utilize the machine with a different width of record strip from that 5 for which the feed disks are adjusted, it is a very simple matter to loosen the nuts 23 and to adjust the feed disks as desired, subsequently gripping them in adjusted position.

In order to transmit rotary feeding movement 10 to the feed shaft 9, an operating handle 24 is mounted exteriorly of the casing 6, this handle being herein disclosed as of the reciprocating lever type. The handle 24 is connected through a detachable attaching device 25 to a toothed rotary 15 gear or driving sector 26 meshing with a pinion 27 which is operatively connected through a clutch mechanism to the driving member 17. This clutch mechanism is only partially herein disclosed, but it will be understood that it cooperates with the driving mechanism as in the Hagemann patent mentioned, to effect rotation of the feed shaft in strip feeding direction.

According to the embodiment of the invention shown in Fig. 3, the structure is generally similar 25 to that above described. However, in this case the conical supporting hubs 19a are not provided with the slots 20 as in the other embodiment but are held in adjusted position upon the feed shaft 9 by means of spacing sleeves 28 received upon the 30 shaft and functioning to hold the disks in properly spaced relation. In this case, as in the other embodiment, the disks are secured in operative position upon the conical supporting hubs by means of nuts 23 threaded to the small ends of 35 the hubs. The disks are prevented from relative rotation upon the shaft 9 by virtue of the hexagonal contour of the shaft cooperating with corresponding hexagonal apertures in the hubs. The proper spacing of the disks on the shaft will 40 be accomplished by selecting spacing disks 28 of the desired length.

In assembling the shaft with the disks 10 and 14 and with the bearings 15 and 16, the bearing 15 with the driving member 17 may first be placed 45 upon the shaft and secured in its operative position thereon by any convenient means, such as by means of the binding washer 29, positioned in a depressed seat in the driving member, and engaging in a notch in the shaft. The shaft is then 50 passed through the bearing hub 8 and the disks are slid on the shaft and adjusted in correctly spaced relation thereon in which they are secured by either of the means above described. Upon passing the end of the shaft through the bearing 55 16 and cam 18, the retaining nut 30 is applied to hold the shaft in its operative position. A plate 31 appropriately attached to the frame 5 is arranged to engage the driving pinion 27 so as to retain it in operative position. This pinion is 60 mounted for rotation on the circular supporting end of the shaft 9.

Since certain changes may be made in the above construction and different embodiments of the invention could be made without departing from 65 the scope thereof, it is intended that all matter contained in the above description or shown in the accompanying drawing shall be interpreted as illustrative and not in a limiting sense.

Having described my invention, what I claim 70 as new and desire to secure by Letters Patent is:

1. In a feed assembly for machines of the character described, in combination, a rotatably supported feed shaft, a plurality of feed disks mounted on said shaft in spaced relation and ad- 75

justable along the shaft, and a gripping device including a contractible hub for holding each of said disks in its operative adjusted position on the shaft.

5. 2. In a feed assembly for machines of the character described, in combination, a rotatably supported feed shaft, a plurality of feed disks mounted on said shaft in spaced relation, a supporting hub for each of said disks mounted for 10 sliding movement along said shaft, each hub having holding means for holding it in position, each disk having an opening in which the corresponding supporting hub is seated, and means for forcing said respective hubs and disks into 15 operative assembled relation with each other and for causing operation of said holding means to hold the respective hub in operative position on the shaft.

3. In a feed assembly for machines of the 20 character described, in combination, a rotatably supported feed shaft, a plurality of feed disks mounted on said shaft in spaced relation, a contractable supporting hub for each disk mounted for sliding movement along said shaft and having 25 a conical supporting surface, each disk having a conical opening complementary with the conical surface of the hub for receiving the latter, and a nut threaded to said hub and cooperating to force the disk into position on the hub and to 30 cause the conical surfaces of the hub and disk opening to engage with each other so as to cause the hub to contract and grip the shaft, thereby to hold the hub in operative position.

4. In a feed assembly for machines of the 35 character described, in combination, a non-circular rotary feed shaft, a supporting bearing and an operative element for said shaft having an opening complementary with said shaft and receiving the latter, said operative element having 40 an integral extension with a cylindrical bearing surface engaging in bearing relation with said supporting bearing, a plurality of disks mounted on said shaft for movement therealong and a gripping device for holding each of said disks in 45 its operative adjusted position on the shaft.

5. In a machine of the character described, in combination, a non-circular feed shaft, a mounting hub having a supporting surface inclined to the shaft axis and having an opening shaped to 50 correspond to said shaft whereby the hub is slideable along the shaft but is held against relative rotation, a strip feed controlling disk having an opening for receiving said hub and having a supporting surface inclined to the shaft axis and 55 engaging in supporting relation with said first mentioned supporting surface, and a retaining nut threaded to said hub and cooperating with the disk for retaining said disk in position upon said hub.

6. In a machine of the character described, in combination, a non-circular feed shaft, a mounting hub having a supporting surface inclined to the shaft axis and having an opening shaped to 60 correspond to said shaft whereby the hub is slideable along the shaft but is held against relative rotation, a strip feed controlling disk having an opening for receiving said hub and having a supporting surface inclined to the shaft axis and 65 engaging in supporting relation with said first mentioned supporting surface, and a retaining nut threaded to said hub adjacent the terminal of said inclined supporting surface of the hub 70 nearest the shaft for forcing said inclined surfaces into supporting engagement with each

other, and to retain the hub and disk in operative assembled relation.

7. In a machine of the character described, in combination, a non-circular feed shaft, a mounting hub having a supporting surface inclined to the shaft axis and having an opening shaped to correspond to said shaft whereby the hub is slideable along the shaft but is held against relative rotation, a strip feed controlling disk having an opening for receiving said hub and having a supporting surface inclined to the shaft axis and 10 engaging in supporting relation with said first mentioned supporting surface, means for retaining said disk in position upon said hub, and a spacing sleeve on said shaft for positioning the disk in 15 a definite operative position longitudinally of the shaft.

8. In a machine of the character described, in combination, a non-circular feed shaft, a mounting hub having a supporting surface inclined to the shaft axis and having an opening spaced to correspond to said shaft whereby the hub is slideable along the shaft but is held against relative rotation, a strip feed controlling disk having an opening for receiving said hub and having a supporting surface inclined to the shaft axis and 20 engaging in supporting relation with said first mentioned supporting surface, a retaining device for forcing said inclined surfaces into supporting engagement with each other and to retain the hub and disk in operative assembled 25 relation, and a spacing sleeve on said shaft for positioning the disk in a definite operative position longitudinally of the shaft.

9. In a machine of the character described, in combination, a non-circular feed shaft, a mounting hub having a supporting surface inclined to the shaft axis and having an opening shaped to correspond to said shaft whereby the hub is slideable along the shaft but is held against relative rotation, a strip feed controlling disk having an opening for receiving said hub and having a supporting surface inclined to the shaft axis and 30 engaging in supporting relation with said first mentioned supporting surface, a retaining device for forcing said inclined surfaces into supporting engagement with each other and to retain the hub and disk in operative assembled 35 relation, and a spacing sleeve on said shaft for positioning the disk in a definite operative position longitudinally of the shaft.

10. In a machine of the character described, in combination, a feed shaft, a mounting hub having a supporting surface inclined to the shaft axis and having an opening receiving said shaft, 40 said hub being longitudinally split whereby the size of its opening may be varied, a strip controlling disk having an opening receiving said hub and having an inclined surface engaging said first mentioned inclined surface so as to 45 contract the hub to grip the shaft, and means for holding the hub and disk in operative assembled 50 position on the shaft.

11. In a machine of the character described, in combination, a feed shaft, a mounting hub having a conical supporting surface and being longitudinally split at its large end and having an opening for receiving said shaft, a strip controlling disk having a conical opening for receiving said conical hub, and a nut threaded to said 65 hub so as to force the conical hub into engagement in the conical opening to contract the hub and bind it in position on said shaft.

12. In a machine of the character described, in combination, an operating shaft having a 70

longitudinal rib, a mounting hub having a supporting surface inclined to the shaft axis and having a shaft-receiving opening shaped to correspond to said shaft and rib whereby the hub 5 is slideable along the shaft but is held against relative rotation, a controlling disk or element having an opening for receiving said hub, and having a supporting surface inclined to the shaft axis and engaging in supporting relation with 10 said first mentioned supporting surface, means for retaining said controlling element in position upon said hub, and means whereby said retaining means cooperates with said hub through said inclined surfaces for securing said assembled 15 hub and controlling element in different adjusted operative positions along said shaft.

13. In a machine of the character described, in combination, an operating shaft having a

longitudinal rib, a contractable mounting hub having a conical supporting surface inclined to the shaft axis and having a shaft-receiving opening shaped to correspond to said shaft and rib whereby the hub is slideable into adjusted 5 positions along the shaft but is held against relative rotation thereon, a controlling element having a conical opening for receiving said conical hub so as to support the controlling element, an attaching extension at the small end 10 of said conical hub, and a retaining member connected to said attaching extension and cooperating with said controlling element to contract said hub through cooperation of said conical surfaces so as to secure the controlling 15 element in position on the shaft.

WALTER ELMER GOCHNAUER.
